UNITED STATES PATENT OFFICE.

SIDNEY BERTRAM SMITH, OF BOGNOR, AND GEORGE MAURICE WRIGHT, OF CHESTERFIELD, ENGLAND, ASSIGNEES TO THE RADIO CORPORATION OF AMERICA, OF NEW YORK, N. Y., A CORPORATION OF DELAWARE.

AERIAL SYSTEM EMPLOYED IN WIRELESS SIGNALING.

Application filed March 8, 1921, Serial No. 450,630, and in Great Britain December 24, 1919.

(GRANTED UNDER THE PROVISIONS OF THE ACT OF MARCH 3, 1921, 41 STAT. L., 1313.)

This invention relates to the aerial systems employed in wireless signaling, and its object is to provide an improved system in which the well known heart-shaped polar 5 diagram can be readily obtained for ascertaining the bearing of a station or for eliminating jamming or for other purposes.

According to this invention we employ a differential transformer the secondary of 10 which is shunted by a variable condenser by means of which the system can be tuned. One primary is connected either to a pair of loop aerials through a tightly coupled radiogoniometer or to a rotating loop aerial, 15 and the other primary is connected to earth and to middle points of the bases of the two loops or to the middle point of the base of the rotating loop. The necessary phase and 20 amplitude adjustment is provided by the insertion of a resistance in series with one of the primary windings.

The only tuning required is effected by 25 means of the condenser and in practice the phases remain unaltered over wide ranges of wave lengths.

Figure 1 of the accompanying drawing is 30 a diagrammatic representation of a simple arrangement in accordance with our invention.

Fig. 2 is a vector diagram illustrating the 35 probable vector relations of currents and electromotive forces existing in Fig. 1.

Fig. 3 is a diagrammatic representation 40 illustrating a further improvement over Fig. 1.

Fig. 4 is a vector diagram of the probable 45 vector relations existing in Fig. 3.

Fig. 5 illustrates the heart shaped polar 50 diagram of the system.

Referring particularly to Fig. 1 the leads 55 A B C and D from two frame or loop aerials at right angles are connected in the usual manner to the field coils of F_1 , F_2 , F_3 and F_4 , of a radiogoniometer, of which the tightly 60 coupled search coil S is connected to the primary P of a differential transformer, of which the secondary winding J is shunted

by an adjustable condenser K by which the 50 complete circuit can be tuned to the desired wave length. A vertical aerial obtained by connexion to the mid points of the radiogoniometer fields is connected through a suitable resistance R to a third winding T of the differential transformer and so to 55 earth. It is desirable to insert between J and the other windings an earth screen E connected to the low potential end of the winding J to minimize direct electrostatic effects. A value of the resistance R can be 60 found such that the heart shaped diagram 65 can be obtained.

A consideration of the vector diagram in 70 Figure 2 will illustrate how this result is obtained. Let EV represent the E. M. F. induced in the vertical wire; then if the 65 resistance R is large compared with the impedance of the remainder of the circuit the current resulting from this E. M. F. will be 75 approximately in phase with it, and can be represented by the vector IV. The vector 70 EF represents the E. M. F. induced in the loop, lagging 90 degrees behind EV, and since the impedance of the loop aerial circuit is mainly inductive the current in this 75 circuit will lag 90 degrees behind EF and can be represented by the vector IF. It is 80 clear that IF and IV are 180 degrees apart in phase and that they will add or subtract according to the position of the search coil S. Adjustment of the current amplitude in 85 the vertical wire can be obtained by the adjustment of the resistance R provided that the initial E. M. F. (EV) is large enough, as is usually the case in practice. It should 90 be noticed that the circuit possesses the important advantage that providing the initial connexions are right a reversal of sense by incorrect adjustment of the circuits is impossible, the only effect produced being an impure minimum.

Figure 3 shows an alternative arrangement 95 possessing a greater selectivity and capable of giving a purer minimum than that given by the circuits of Figure 1. In

this case a loosely coupled jigger is employed. The primary P and the balancing coil B are connected to the search coil of the radiogoniometer and tuned by means of 5 the variable condenser K_1 , the jigger secondary J being loosely coupled to P and tuned by the variable condenser K_2 . When the correct value of R and a suitable adjustment of coupling between B and T are obtained 10 the heart-shaped polar diagram results. We prefer to couple T to the coil B rather than to P in order to make certain that in the direction of minimum signals 15 on the polar diagram an incoming signal shall produce no current in the circuit K_1 P B. Were T coupled to P (and consequently to J) the best adjustment would be obtained when the currents in P and T were of such intensities and in such directions 20 as to produce zero magnetic field in J. The presence of any current in the circuit K_1 P B may cause an undesirable shift in phase of the currents in the loop aerials and so render it difficult to obtain a perfectly pure 25 minimum.

In order to obtain the purest minimum we find it best to arrange the inductance of the coil T that the wave length of the vertical aerial circuit is a little shorter than 30 the wave length it is desired to receive. The reason for this will be evident from a closer consideration of the vector diagram of the E. M. F.'s and currents in the circuits. In Figure 4 let EF represent the E. M. F. induced 35 in the frame aerial by the incoming wave. Now owing to the fact that this aerial possesses a certain resistance the currents in it will not lag exactly 90 degrees behind EF, but will have a phase angle 40 slightly less than 90 degrees as shown by the vector IF. EV represents the E. M. F. induced by the wave in the vertical aerial circuit. Again owing to the fact that this circuit possesses inductive and capacity reactance, the current can never be exactly 45 in phase with EV (except in the particular case of resonance). Consequently the vector IV may occupy either the position IV or Iv, depending upon whether inductive or capacity reactance predominates. The best 50 balance will obviously be obtained when this current vector occupies the position IV, when capacity reactance predominates in the vertical aerial circuit, i. e. when the tune of this circuit is a little shorter than the wave 55 length to be received.

Referring to Figure 5, which is a reproduction of the heart-shaped polar diagram of the system, it can be shown that the maximum slope of the polar curve occurs at the 60 points X and Y. At these points the ordinate OX is equal to OY, consequently if the search coil is adjusted to such a position that no change of signal strength occurs on 65 reversing the connexions to it, i. e. upon

rotating the polar diagram through 180 degrees, this position will represent the direction of the incoming signal. Also the determination will have been made in a region on the polar curve where a given change in 70 angle of the radius makes the greatest change of difference in the two signal strengths.

A simple form of stand-by can also be obtained in which the system receives approximately equally in all directions horizontally by short circuiting the resistance R; in which case ordinary vertical aerial reception results, superimposed upon the relatively weak directional effect of the 80 frame aerials.

What we claim is:

1. A directional aerial system comprising an aperiodic loop grounded through a resistance of such value that the antenna voltage and current in the ground connection are substantially in phase. 85

2. A directional aerial system comprising a pair of aperiodic crossed loops, a ground connection for said loops and a resistance in 90 the ground connection of such value that the antenna voltage and current in the ground connection are substantially in phase. 95

3. A directional aerial system comprising an aperiodic loop, an inductance in said loop, 100 a ground connection to a mid point of said inductance, and a resistance in the ground connection of such value that the antenna voltage and current in the ground connection are substantially in phase. 105

4. A directional aerial system comprising an aperiodic loop grounded through a resistance of such value that the antenna voltage and current in the ground connection are substantially in phase, and means for combining the loop and ground currents. 110

5. A directional aerial system comprising a pair of stationary crossed loops and coupling coils therein, a ground connection to a mid point of said coils, a resistance in the ground connection of such value that the antenna voltage and current in the ground connection are substantially in phase, a rotatable coil for coupling with the loop coils, and 115 a circuit including said coil associated with the ground connection.

6. A directional aerial system comprising a loop aerial containing impedances adapted to give substantially a 90° phase relation between the current and voltage, a ground connection for said loop containing a resistance of such value that the antenna voltage and current in the ground connection are substantially in phase, and means for combining currents of the loop and ground connection. 125

7. In a wireless direction finder system, comprising a receiver, the combination of an aperiodic loop aerial, a ground connection from the mid-point of said loop, means for adjusting currents in said loop and ground 130

connection to substantial equality and opposite phase in said receiver for waves from a certain direction and comprising a resistance in said ground lead of at least sufficient value to insure that antenna voltage and current, in said ground connection are substantially in phase, and means for combining currents from said loop and said ground connection.

10 8. In a wireless direction finder system, comprising a receiver, the combination of an aperiodic loop aerial, a ground connection from the mid-point of said loop, means for adjusting currents in said loop and ground connection to substantial equality and opposite phase in said receiver for waves from a certain direction and comprising a resistance in said ground lead of at least sufficient value to insure that antenna voltage and current 20 in said ground connection are substantially in phase and a circuit associated with said loop and said ground connections.

9. In a wireless aerial system, the combination of an aperiodic loop aerial, a ground connection for the loop adapted to provide a vertical aerial, a circuit associated with each of said aerials and a resistance in one of the aerials of such value that the antenna voltage and current in said aerial are substantially 30 in phase.

10. In a wireless aerial system, the combination of an aperiodic loop aerial, a ground connection for the loop adapted to provide a vertical aerial, a circuit associated with a portion of the aerial carrying currents due 35 to loop and vertical aerial reception, and a resistance in the vertical aerial of such value that the antenna voltage and current in said aerial are substantially in phase.

11. In a wireless aerial system, the combination of an aperiodic loop aerial, a coil deriving currents from the loop aerial, a resistance, a second coil deriving currents from the vertical aerial connected to the loop and to earth through the resistance, said resistance being of sufficient value to insure that antenna voltage and current in said ground connection are substantially in phase, a circuit for combining the currents derived from 45 said coils and tuning means in said circuit.

12. In a wireless aerial system, the combination of an aperiodic loop aerial, an inductance coil therein, a resistance, a connection to the mid point of said coil and to earth through said resistance to secure a vertical aerial, said resistance being of such value as to insure that antenna voltage and current in said ground connection are substantially in phase, a coupling coil in the vertical aerial and a circuit associated with each of said coils.

13. In a wireless aerial system, the combination of an aperiodic loop aerial, a coil deriving currents from the loop aerial, a connection from said loop to earth adapted

to provide a vertical aerial, a resistance in one of the aerials and of such value that antenna voltage and current in said vertical aerial are substantially in phase, a coil associated with the vertical aerial, a circuit associated with each of said coils and tuning means in said circuit.

14. In a wireless aerial system, the combination of an aperiodic loop aerial, a coil therein, a resistance, a coil connected from the mid point of said first mentioned coil to earth through said resistance, said resistance being of such value that the antenna voltage and current in said connection are substantially in phase, adapted to provide 75 a vertical aerial, a third coil associated with the first mentioned coil, a fourth coil associated with the second mentioned coil, a circuit for combining the currents from the third and fourth mentioned coils and tuning means in said circuit.

15. In a wireless aerial system, the combination of an aperiodic loop aerial, a coil deriving currents from the loop aerial, a connection from said loop to earth adapted 90 to provide a vertical aerial, said vertical aerial being tuned to a shorter wave length than the signal to be received, a resistance in one of the aerials, a coil associated with the vertical aerial, a circuit associated 95 with each of said coils and means for varying the tuning of said circuit.

16. In a wireless aerial system, the combination of an aperiodic loop aerial, a ground connection for the loop aerial adapted to 100 form a vertical aerial, means for combining currents from said aerials and a resistance in the ground connection of such value that the antenna voltage and current in said connection are substantially in phase.

17. In a wireless aerial system, the combination of a loop, a differential transformer, one primary of which is connected to the loop, the other primary being connected to earth and to the frame in 110 such a manner as to form an aerial with uniform radiation and a resistance in series with one of the primaries.

18. In a wireless aerial system, the combination of a loop, a differential transformer, one primary of which is connected to the loop, the other primary being connected to earth and to the loop in such a manner as to form an aerial with uniform radiation, a resistance in series with one of the primaries and tuning means connected to the secondary of the differential transformer.

19. In a wireless aerial system the combination of an aperiodic loop, a differential transformer, one primary of which is connected to the loop, the other primary being connected to earth and to the loop in such a manner as to form an aerial with uniform radiation and a resistance in series with one of the primaries.

20. In a wireless aerial system the combination of an aperiodic loop, a differential transformer, one primary of which is connected to the loop, the other primary being connected to earth and to the loop in such a manner as to form an aerial with uniform radiation, a resistance in series with one of the primaries and tuning means con-

nected to the secondary of the differential transformer.

In testimony that we claim the foregoing as our invention, we have signed our names this 14th day of February, 1921.

SIDNEY BERTRAM SMITH.
